UNITED STATES PATENT OFFICE.

JOSEPH H. BECK AND GEORGE BEDFORD, OF BROOKLYN, NEW YORK.

PLAYER-PIANO.

1,227,368.

Specification of Letters Patent.

Patented May 22, 1917.

Application filed February 17, 1915, Serial No. 8,800. Renewed January 30, 1917. Serial No. 145,569.

To all whom it may concern:

Be it known that we, JOSEPH H. BECK and GEORGE BEDFORD, citizens of the United States, residing at Brooklyn, in the county 5 of Kings and State of New York, have invented certain new and useful Improvements in Player-Pianos, of which the following is a specification.

This invention relates to manually actuated mechanism for operating the sliding lower panel or door of a player-piano casing and extending the pedals forwardly through the same, also for withdrawing the 10 pedals and closing the door. Its object is to insure the perfect performance of these 15 operations in due order by simple means and without strain. This object is attained by the construction and combination of parts hereinafter more particularly set 20 forth and claimed.

In the accompanying drawings:

Figure 1 represents a rear elevation of the mechanism embodying our invention, with the door open;

Fig. 2, a similar view with the door down or closed;

Fig. 3, the same taken in the position after the pedals have been withdrawn within the casing, but before the door has begun to 30 descend;

Fig. 4, a section through the upper part of the casing beside the operating shaft looking to the left on the line 4—4 of Fig. 1;

Fig. 5, a detail front elevation of the handle and proximate part of the casing showing said handle in full lines in the position which it occupies in accordance with Fig. 1, and in dotted lines in the positions corresponding to Figs. 2 and 3.

40 A designates the casing, B the pedals and C the door or sliding lower panel of a player piano. The said pedals are mounted on a pedal bar *b*, carried by two supporting bars D D', which are pivoted within said 45 casing in bearing blocks F F' and bent to avoid the proximate lower part of the casing in their forward and downward movement. The bar D has a retarding spring E of torsion type attached to it and provided with rubber cushion as in our application Serial No. 854,479. Said arm or bar D has an integral lateral arm *d* that carries a bifurcated removable arm G, between which and bearing block F a spacing sleeve 50 *g* is located on lateral arm *d*. A long operating bar H is pivoted at its lower end be-

tween the bifurcations of the upper end of arm G and at its upper end to the terminal cranked arm *i* of the operating rock-shaft I, which extends horizontally forward through 60 said casing A, being mounted in suitable bearings and provided with a handle in front of the casing; by means of which handle the said pedals are turned at will down and out through the opening of the door or 65 panel C or backward and upward through said opening to a position within said casing.

Said shaft I, at the point of junction of said integral arm *i* therewith, is provided 70 with a door operating arm J fast on said shaft to turn therewith. This arm is provided with a hook or bent extension *j* which may be in a separate piece rigidly bolted thereto as shown. This hook is arranged to 75 engage in an open end slot *k* between the bifurcations of the nearer arm of a large bell-crank lever K, preferably of three ply maple wood, which is more durable than a wooden block in one piece, said lever K being pivoted at its angle to the casing A. The lower end of the other arm of said bell-crank lever K is provided with a roller *m* arranged to bear on the proximate and shorter arm of a lever L, which is the immediate means of raising the door suspended by a long link M from the end of the longer arm of lever L. A helical spring N, connected at its upper end to said casing A and at its lower end to the longer arm of 80 lever L near the pivot P of the latter, assists in some degree the lifting of said door and retards its descent as hereinafter described. The upper surface of the short arm of lever L is provided with a raised incline having a concave face *l*, up which the said roller travels in the last stage of its lifting action on said lever, this construction insuring an even and final action in said movement and preventing an upward kick by 85 the short arm of the lever L when the roller *m* reaches its lowest position, by reason of the space that otherwise would be left between said roller and said short arm.

The arrangement of the aforesaid parts 90 is such that when the shaft I is rocked to withdraw the pedals into the casing the action on the pedals begins at once, and the arm J and hook *j* of said shaft travel a short distance before entering slot *k*. The 95 action of said hook on the bell-crank lever K then proceeds and the roller *m* runs down

the incline *l* and along the shorter arm of the lever *L* at first freely and without effect for reasons hereinafter stated, but afterward balancing said door until said roller 5 passes a certain point of the latter lever and a certain position with relation to the pivot *P* of the latter, whereupon its counterbalancing effect is removed and the door thereupon falls and closes. As the roller 10 reaches this point the pedals are held upright just within the casing, so as not to impede the descent of the door. The handle is then in its upper dotted line position. The open-door position of lever *L* is upwardly inclined, the closed-door position downwardly inclined, hence the roller *m*, as said lever passes from the former position to the latter, soon ceases to have any effect in accelerating its descent. This roller *m* 15 never passes along lever *L* so far as said pivot. The precise determining point of its change of action from counterbalancing to depression, as above explained, will depend on the pivotal point of the bell-crank lever 20 *K* and the length, inclination and form of the arm of said lever carrying said roller *m*. The higher dotted line position of the handle *I* in Fig. 5 is that which it occupies 25 when the door is quite closed and the pedals 30 are in their rearward position within the casing.

During the first stage of the above movement while the hook *j* has not yet entered the slot *k* it is obvious that the shaft *I* is spared all strain from the weight of the door and intervening parts and that there is no wear or strain on hook *j*, levers *K* or *L* or the pivots of these latter two parts.

When the roller *m* is in its lowest position 40 (Fig. 1) its position with relation to the pivotal point of said bell crank lever, to which the lower arm of the latter connects it, is nearly vertical and will lock the long arm of said lever and the said door against accidental descent. The open-end construction 45 of slot *k* leaves bell-crank lever *K* without attachment to the shaft *I*, though the arm *J* of said shaft is in intermittent free sliding contact with the walls of said 50 slot as described. This freedom of said bell-crank lever makes all the operative parts between arm *J* and the door independent of said shaft at will. This is especially important if the guideways and proximate 55 parts of the wood-work below said shaft and its bearings be made as a frame or panel removable with the door from the casing, as we have sometimes done; but whether this construction of the woodwork be 60 adopted or not, there are manifest advantages in the ready separability of said bell-crank lever and said arm carried by the shaft. Repairs, cleaning and other operations will be facilitated and the shaft is 65 made independent for such purposes besides

being automatically freed from strain and weight during a part of its movement as already stated. This relief could not occur if the point of separability were not in close proximity to said shaft.

By turning the handle of shaft *I* in the opposite direction, thus reversing the order of its three positions, the door of course is first lifted by the action of shaft *I*, arm *J*, hook *j*, slotted bell-crank *K*, lever *L* and link *M*. The continued turning of the handle and shaft *I* causes the roller to travel back along the short arm of lever *L* and up the inclined concaved face *l* without further effect on said lever or said door, though continually in contact with said lever, because of the calculated relation of the line of travel of said roller and the inclination of said short arm in the fully open position and the curvature and inclination of said concave face. As the roller passes up said curved incline reaching the end of its rearward play, the hook *j* passes out of the slot *k* and ceases to exert any pressure on the slotted arm of said lever *K*. The final part of the movement of shaft *I*, in returning to their original position first above described and indicated by full lines, will move quite freely so far as the door operating devices are concerned. In the meantime the treadles are carried forward and downward by the action of said shaft *I* and handle, arm *i*, long rod or bar *H*, arm *G* and supporting bar *D*, the final part of this movement lowering the treadles to operative exterior position, being aided in this by the action of the torsion spring above mentioned.

Two fixed stop pins *Q* and *R* attached to the rear face of the front of casing *A* are arranged for contact respectively with each of the two arms of bell-crank lever *K*, so that said lever cannot turn too far on its pivot in either direction and said arms will be always in the right position and arrangement to operate. The upper pin *Q*, by stopping the slotted arm of said lever from descent after the hook *j* has escaped from the slot *k*, and thus disengaged lever *K*, will keep the roller *m* on the other arm of said bell-crank lever in contact with the short arm of lever *L* and thus prevent the door from dropping behind the pedals so as to obstruct their withdrawal as they are raised and drawn over into the casing as already described.

Having thus described our invention, what we claim as new and desire to secure by Letters Patent is:

1. In combination with pedals and a shaft 125 and connections for extending and withdrawing said pedals, a door arranged to open before such extension and close after such withdrawal, a part carried by said shaft, means attached to and moving with 130

said door to operate the same and a movable device provided with an open ended slot for separable engagement with the part carried by said shaft, said device being interposed between the latter and said means to actuate the latter.

2. In combination with pedals and a rock-shaft and connections for extending said pedals into operative position and withdrawing them therefrom, a sliding automatically closing door, a hook carried by said shaft, a lever for opening said door and pivotally mounted means interposed between said hook and lever and provided with an open ended slot for separable engagement with said hook to transmit motion therefrom to said lever during a part of the movement of the former.

3. In combination with pedals and a rock-shaft and connections for extending said pedals into operative position and withdrawing them therefrom, a sliding automatically closing door, a hook connected to said shaft, a lever for opening said door, and a bell-crank lever bearing with one arm on said lever and having its other arm bifurcated to slidably and separably receive said hook which moves from the bifurcations of said arm when the door is in its raised position, to disconnect the pedal operating mechanism from the door operating mechanism.

4. A rock-shaft, pedals, connections for extending and withdrawing said pedals and an automatically closing door, in combination with a bell-crank lever having a bifurcated arm, a part carried by said shaft engaging said arm between the bifurcations thereof, a lever acted on by the other arm of said bell-crank lever to open said door, said part disengaging with the bifurcated arm when the door has been completely opened, and stops limiting the movement of said bell-crank lever in either direction.

5. In combination with pedals and means for extending and withdrawing them, a sliding door arranged to open before such extension and close after such withdrawal, a lever connected to and moving with said door, a movable part actuated by said means and bearing on one arm of said lever by traveling contact and arranged to free said lever on reaching a certain point thereof, said lever being provided with an inclined concave face continuous with the remainder of the top or upper face of this lever up which said part will travel in moving toward the end of said arm of said lever, for the purpose of preserving continuous contact between said parts and preventing jar and the reverse movement of the door.

6. In combination with pedals and means for extending and withdrawing them, a sliding door arranged to open before such extension and close after such withdrawal, a lever connected to and moving with said

door, a movable part acting on said lever and normally actuated by said means but freely separable from said shaft at a point in proximity thereto and automatically detached therefrom at the beginning of the pedal-withdrawing movement and a stop arranged for contact with said part to prevent the closing of the door when thus freed from said operating means.

7. In combination with pedals and a shaft and intervening connections for extending and withdrawing said pedals, a vertically movable door arranged to open before such extension and close after such withdrawal, a lever suspending said door, adapted to raise the same and provided at the rear end of its actuated arm with a raised inclined concave face and a part operated by said shaft and having a traveling contact with said arm of the lever and said concave face.

8. In combination with pedals and a shaft and intervening connections for extending and withdrawing said pedals, a vertically movable door arranged to open before such extension and close after such withdrawal, a lever for suspending and raising said door, a spring connected to said lever for retarding the descent of said door and expediting its ascent, a bell-crank lever carrying a roller which acts on the former lever and having a bifurcated arm and a part carried by said shaft and engaging the bifurcations of said bell-crank lever, but arranged to be free therefrom during the first part of the pedal withdrawing movement.

9. Pedal extending and withdrawing mechanism and door operating mechanism, in combination with an actuating shaft and connections therefrom to each of said mechanisms, the door-operating mechanism comprising a lever for suspending and lifting the door, said lever being provided on its shorter arm with a raised inclined face continuous with the remainder of the upper face of said lever and a movable part continuously in contact with said lever, and traveling freely thereon from said inclined face to the proximity of the pivotal point of said lever and back again acting thereon to lift said door during a part only of its movement in one direction and to free said lever and door for descent only at the final point of its movement in the other direction.

10. In combination with a vertically movable door of a piano-casing opening and closing to permit the protrusion and withdrawal and protection of the pedals, a lever suspending said door from its long arm and provided on the top of its short arm with a concave face inclined upwardly away from its pivot, but continuous with the remainder of the top of said lever, an actuating shaft and a bell-crank lever arranged between said shaft and the said suspending lever, actuated by said shaft and bearing with

traveling contact on the said suspending lever from said inclined face to the pivot of the latter, said part while stationary locking the door in its highest position, but 5 causing its descent when its point of contact approximately reaches the pivot of said suspending lever.

In testimony whereof, we have signed our

names to this specification in the presence of two subscribing witnesses.
